3 Claims. (Cl. 52—88)

ABSTRACT OF THE DISCLOSURE

A reinforced concrete arch structure having a pre-stressed core imbedded in the concrete and comprising a number of sections consisting of parts adapted to be assembled in the field and to be pre-stressed during or after erection.

The herein disclosed invention relates to concrete reinforcing structures and has for an object to provide a prestressed reinforcing structure having both a compression member and a number of tension members.

Another object of the invention resides in providing a structure which may be stressed in the field or during its fabrication.

A still further object of the invention resides in providing stressing means forming a part of the reinforcing structure and embedded with the same in the concrete.

A feature of the invention resides in constructing the compression member in sections of ceramic or similar material and preferably hollow and in the form of a tube with the ends of adjacent sections abutting one another.

Another object of the invention resides in providing a construction by means of which a number of reinforcing structures may be arranged in the form of an arc of a circle whereby the reinforcing members may be used in arches.

An object of the invention resides in providing plates bearing against the ends of the compression member and with the tension members extending through the plates and threaded to receive nuts which when tightened up, stress the reinforcing structure.

Other objects of the invention reside in the novel combination and arrangement of parts and in the details of construction hereinafter illustrated and/or described.

In the drawings:

FIG. 1 is a perspective view of a concrete reinforcing structure illustrating an embodiment of the invention.

FIG. 2 is a longitudinal sectional view of a beam or joist in which a reinforcing structure similar to that shown in FIG. 1 has been employed and taken on line 2—2 of FIG. 3.

FIG. 3 is a cross sectional view taken on line 3—3 of FIG. 2.

FIG. 4 is a view similar to FIG. 2 showing a section of an arch with a number of reinforcing structures arranged in the form of an arc.

FIG. 5 is a sectional view taken on line 5—5 of FIG. 4 and drawn to a greater scale.

FIG. 6 is a plan sectional view of the stressing means shown in FIG. 5 and taken on line 6—6 of FIG. 5.

FIG. 7 is a fragmentary of a modification of the reinforcing structure shown in FIGS. 4, 5, and 6.

In the construction of pre-stressed reinforced concrete construction the common practice has been to pre-stress the tension members while they were erected in the forms and to cast the concrete about the same while so held. This requires rather complicated and heavy machinery and slows down the process of casting the concrete building components in which the reinforcing structures are used. With applicant's invention the reinforcing structure is pre-stressed before insertion in the forms with the stressing means forming part thereof.

2

Applicant's reinforcing structure as used in beams and joists is best shown in FIGS. 1, 2, and 3 and comprises a compression member 10 and a plurality of tension members 20. Cooperating therewith is stressing means 30 and 5 which is disposed at the ends of the compression member 10.

The compression member 10 consists of a number of sections 11 which are tubular in form and which have tubular walls 12 with a bore 13 therein. These sections have ends 14 and 15 which abut each other and which taken in their entirety form the elongated compression member 10. The sections 11 of the compression member 10 are preferably constructed of a non-ferrous material such as a ceramic material or of concrete. Ordinary 15 sewer tile have been found suitable for the purpose.

The tension members 20 consist of rods formed of metal and which have ends 21 extending outwardly beyond the ends 14 and 15 of the end sections 16 and 17 of compression member 10.

20 The stressing means 30 of the reinforcing structure includes two caps or plates 31 and 32 which are constructed of metal and which butt up against the ends 14 and 15 of the last sections 16 and 17 of the compression member 10. These plates have holes 33 drilled in the same and through which the ends 21 of the rods 20 extend. These ends are threaded to receive nuts 34 which bear against the outer surface 35 of the plates 31 and 32.

By tightening up the nuts 34 on the ends of the rods 20, the compression member 10 is placed in compression and the tension members 20 are stressed in tension. Thus 25 a pre-stressed concrete reinforcing structure is provided which may be inserted into the forms for the concrete building components prior to the casting of the same.

For the purpose of illustrating the application of the 30 invention a portion of a building component 40 has been shown in FIGS. 2 and 3. This component may be used in constructing a floor or a roof. This component is elongated in form having sides 41 and 42, ends 43 and 44, a top 45 and a bottom 46. The pre-stressed reinforcing member is imbedded in the concrete 47 forming said component with the entire reinforcing member covered with concrete. The same may if desired be placed nearer the bottom 46 to bring more of the upper portion of the component in compression. In the sides 41 of the component are formed grooves 48 and on the sides 42 are 35 tongues 49. The tongue 49 of one component fits into the groove 48 of the adjacent component to lock the parts together and provide an interlock between the various components and an unitary construction.

In FIGS. 4, 5, and 6 the reinforcing structure indicated 40 by the reference numeral 50 has been shown as applied to an arch. Instead of a long straight reinforcing structure, several short units are employed, which are connected together to form a composite structure arcuate in form. Four of the units of this structure have been 45 shown in FIG. 4 and designated by the reference numerals 51, 52, 53, and 54. Each of these units consists of a compression member 55 formed with three tubular sections 56, 57, and 58. These units also have tension members, the units 51 and 53 having tension members 59, 60, 61, 62, and 63 and the units 52 and 54 having tension members 64, 65, and 66. Each unit has three tension members, and the tension members of one unit are interposed between those of the other unit, so that the members are sixty degrees apart. If desired, however, the tension members of one unit may be placed closer to those of the adjoining unit.

The stressing means 70 of the reinforcing structure 50 consist of plates 67 and 68 for each section having holes 75 through which the tension members 61, 62, 63, 64, 65, and 66 and nuts 69 screwed on the threaded ends of the tension members extend, the same as with the other

form of the invention. Due to the curvature of the completed reinforcing structure the plates 67 and 68 of adjoining units become spaced at the convex portion of the arch and contact one another at the concave portion of the arch. In order to transmit stresses from one unit to the other, the two adjoining caps between the units are made integral with a connecting portion 71 therebetween. The parts may be welded together or a single plate employed, bent at 72 and 73 to form the connecting portion 71 and with the opposite edges contacting and welded together. If desired the composite structure may be cast from malleable iron or similar material.

Opposite the nuts 69 and in the plates opposite the plates engaged by the nuts 69 are openings 74, and through which a wrench may be inserted to engage the nuts and manipulate the same.

Concrete indicated at 76 is poured into the forms in which the reinforcing structure is positioned to form building components similar to those previously described.

In FIG. 7 is shown a modification of the reinforcing structure for use in arches. This structure is similar to the foregoing structure, and the same reference numerals will be used to designate like parts. The plates 67 and 68 are the same except the connecting portion 71 is dispensed with. Also holes 75 have been substituted for the openings 74. In this form of the invention the tension members extend through both of the plates 67 and 68. These members, between the plates 67 and 68 have sleeves 77 mounted on them and which form spacers serving the same purpose as the connecting portion 71 of the other form of the invention. Beveled washers 78 underlying the nuts 69 provide a square seat for said nuts.

The method of using the invention is obvious. The parts can be assembled at the factory and shipped in an erected 35 form or the parts can be erected at the site where the reinforcing structure is to be used. In either case a trough is provided of the desired length and the compression member sections arranged in the trough in abutting relation. The end plates are then held in position while the 40 tension members 20 are threaded through the holes 53 in the end plates and the nuts 54 applied. The nuts can then be tightened to give the desired initial stress.

The advantages of the invention are manifest. Heavy cumbersome equipment for the purpose of stressing the 45 tension members is dispensed with and also the supporting structure for temporary stressing the tensile members is done away with. By the use of hollow tubes for the compression members less concrete is employed than would otherwise be necessary. The reinforcing structure

may be rapidly assembled and stressed and when placed in the forms, may be completely covered with concrete to form the ultimate building component.

Changes in the specific form of the invention, as herein described, may be made within the scope of what is claimed without departing from the spirit of the invention.

Having described the invention, what is claimed as new and desired to be protected by Letters Patent is:

1. In a reinforced concrete arch structure having a pre-stressed core imbedded in the concrete, said core comprising a number of sections each having:

- (a) an elongated compression member,
- (b) a plurality of elongated rods, threaded at their ends and disposed about the compression member,
- (c) end plates at the ends of the compression member and against which the compression members bear,
- (d) said rods extending through said plates,
- (e) nuts on said rods engaging said plates to compress the compression member and tension the rods,
- (f) the plates at the adjoining ends of the sections being arranged in V-shaped formation and
- (g) connecting members between the adjoining plates for holding the plates in fixed relation.

2. A reinforced concrete arch structure according to claim 1 in which:

- (a) at least one of the connecting members is integral with both adjoining end plates.

3. A reinforced concrete arch structure according to claim 1 in which:

- (a) at least one of the connecting members utilizes one of the rods which extends through both of the adjoining plates and
- (b) a sleeve encircling said rod and engaging both of said plates.
